UNITED STATES PATENT OFFICE.

CHRISTOPHER C. MILLER, OF RICHLAND, AND JOHN W. ROWE, OF MARTINSVILLE, ILLINOIS.

END-GATE.

SPECIFICATION forming part of Letters Patent No. 441,575, dated November 25, 1890.

Application filed July 10, 1890. Serial No. 358,305. (No model.)

To all whom it may concern:

Be it known that we, CHRISTOPHER C. MILLER, of Richland, in the county of Pulaski, and JOHN W. ROWE, of Martinsville, in the county of Clark and State of Illinois, citizens of the United States, have invented certain new and useful Improvements in End-Gates for Wagons; and we do hereby declare the following to be a full, clear, and exact description 5 of the invention, such as will enable others skilled in the art to which it appertains to make and use the same.

Our invention relates to end-gates for wagon-beds; and it consists in the new and improved construction, arrangement, and combination of parts of a combined end-gate and scoop-board which will be hereinafter fully described and claimed.

Referring to the accompanying drawings, 20 Figure 1 is a perspective rear view of a wagon provided with our invention, showing the end-gate closed. Fig. 2 is a similar view showing the gate opened. Fig. 3 is a perspective rear view showing the gate suspended on top of the wagon-bed, thereby leaving the end of the bed open. Fig. 4 is a detail view, on an enlarged scale, of one of the spring-clamps; and Fig. 5 is a similar view of one of the side wings 25 of the end-gate.

30 The same letters of reference indicate corresponding parts in all the figures.

Referring to the several parts by letter, A indicates the end-gate proper, which may be of wood or other suitable material, to the ends 35 of which are secured the segmental side wings B B, which are preferably made of metal. These side wings are formed near their lower rear corners with the open slots B', in which fit pins C C, extending out from the project- 40 ing rear end of the wagon-bottom. The wings are preferably re-enforced at the point where they are slotted to give them increased strength, thickness, and durability by the re-enforcing plates b, as shown.

45 The end-gate receives additional support from the projecting rear end of the bottom of the wagon-bed.

To the rear ends of the side-boards of the wagon-body are secured the spring-clamps D, 50 the free ends of which are provided with the

conical points or projections E, extending inward, as shown, and adapted to engage with openings F, formed in the wings B near their curved edge, springing or passing through the said openings into registering openings W' 55 in the ends of the sides W of the wagon-body. It will be seen that by this construction, when the end-gate is closed, as in Fig. 1, the cone-shaped pins E will pass through the upper openings F of the side wings, and will 60 thus hold the end-gate locked in its closed position, while, when the gate is opened, as shown in Fig. 2, the cone-pins will pass through the lower openings F of the side wings, and thus hold the gate in its open position to serve 65 as a scoop-board. When the cone-pins of the spring-clamps are in the lower holes, the gate can be turned up over the end of the wagon-body and suspended on top of the same, as shown in Fig. 3 of the drawings, thus leaving 70 the rear end of the wagon-body entirely open.

To prevent brush or cornstalks from wedging between the sides W of the wagon-bed and the side wings B B, we have provided curved metal guards G, which project over 75 the curved edges of the side wings when the gate is closed, as seen in Fig. 1.

The gate may be used with or without side-boards S, and in either case may be used as a scoop-board. When the side-boards are 80 used, an end-board I, of the same width as the side-boards S, is secured on the gate by slats i, fitting into staples i' on the gate, hooks w² being secured to the rear ends of the side-boards S, which hook into eyes i², secured in 85 the ends of the end-board I.

Having thus described our invention, what we claim, and desire to secure by Letters Patent, is—

1. The combination of the end-gate having 90 the side wings B formed with the openings F, and having the open slots B' at their lower rear corners, the supporting-pins C C, and the spring-clamps having the cone-pins at their free ends, substantially as set forth.

2. The combination of the end-gate having 95 the side wings B formed with the openings F, and having the open slots B' at their lower rear corners, the supporting-pin C, the spring-clamps having the cone-pins at their free ends, 100

and the curved guards G, substantially as set forth.

3. The combination of the end-gate having the side wings B formed with the openings F 5 and the open slots B', and having the staples i', the supporting-pins C, the spring-clamps having the cone-pins at their free ends, the side-boards S, having the hooks w² at their rear ends, and the end-board I, having the

slats i, and having the eyes i², secured in its ends, substantially as set forth.

In testimony whereof we affix our signatures in presence of two witnesses.

CHRISTOPHER C. MILLER.
JOHN W. ROWE.
